UNITED STATES PATENT OFFICE.

DENIS M. HOLLINS, OF BLACKBURN, ENGLAND, ASSIGNOR TO DRAPER COMPANY, OF HOPEDALE, MASSACHUSETTS, A CORPORATION OF MAINE.

TAKE-UP MOTION OF LOOMS FOR WEAVING.

1,130,599.

Specification of Letters Patent.

Patented Mar. 2, 1915.

Application filed December 15, 1913. Serial No. 806,748.

To all whom it may concern:

Be it known that I, DENIS MACHELL HOLLINS, a subject of King George V of Great Britain, residing at Blackburn, in the county 5 of Lancaster, England, have invented certain new and useful Improvements in or Connected with the Take-Up Motions of Looms for Weaving, of which the following is a specification.

- 10 This invention relates to loom take-up motions and particularly to the positive worm driven take-up motions which are employed in looms for weaving fustian or velvet or like fabrics, and the object of my invention 15 is to provide means for automatically stopping the take-up immediately the weft fork motion operates on breakage or absence of weft, or on the actuation of the weft replenishing mechanism when weft exhaustion 20 is detected by a filling feeler, in order that the next pick inserted after a change has been made may be beaten up close against the last pick, it being advantageous in weaving fustian or velvet to have the picks of 25 weft closely laid adjacent each other.

My invention, and the manner in which it is carried into practice, will be described with reference to the accompanying drawing, in which:—

- 30 Figure 1 is a front elevation of so much of a positive worm driven take-up motion as is necessary for the purpose of enabling the improvements to be understood; while Fig. 2 is a section on the line A—A, Fig. 1, looking in the direction of the arrow B, certain of the parts shown in Fig. 1 being omitted from this figure.

Referring to the drawing, 1 represents the sand beam or roll, and 2 the cloth beam or 40 roll. Fast on the shaft of the sand roll is a spur wheel 3 which meshes with a pinion 4 integral with or secured on the axis of a worm wheel 5. This worm wheel meshes with a worm 6 fast on a shaft 7 on the front 45 end of which is loosely mounted a spur wheel 8, to which motion is transmitted through spur gears 9, 10 and 11 from the tappet shaft of the loom. The above parts and their arrangement with means 50 to clutch the gear 8 to the shaft 7, constitute an ordinary form of worm-driven take-up motion and do not in themselves form a part of my invention, which consists in providing means whereby the gear 8 is 55 unclutched from the shaft 7 immediately

the weft fork motion operates on breakage or absence of weft or, if a weft feeler mechanism be employed, in case such mechanism detects substantial weft exhaustion.

In carrying out my invention as applied 60 in connection with a weft fork motion, I mount loosely on the usual stop or change rod 12, or on some other conveniently located rod, spindle or stud, a lever or arm 13 whose upper end 13' is positioned in the 65 path of a projection on the usual slide of the weft fork motion, so as to be rocked in a forward direction when the said weft fork slide is moved, in the ordinary manner, on the weft for detecting absence or breakage 70 of weft. The boss 13² of the lever 13 is provided with a short extension or arm 13³ carrying a pin, lug or the like 14 which extends in the path of and is adapted to engage the upper end 15' of a lever 15 pivotally mounted 75 on a stud 16 carried by a suitable fixed bracket 17. The lower end or arm 15² of the lever 15 is formed or provided with a circular portion or ring 15³ which is adapted to pass over, and occupy a position concentric 80 with, a boss 8' on the spur wheel 8.

On the outer or forward end of the shaft 7 is secured an arm 18 carrying at its outer end a stud 19 which is adapted to move freely through an opening in the arm. 85 Near the inner end of the stud 19 is a flange, collar, or the like 20, which is normally held in engagement or contact with the face of the boss 8' and with the face of the circular portion or ring 15³ of the lever 15 by means 90 of a spring 21 confined on the stud 19 between the flange or collar 20 and the arm 18.

In the boss 8' of the wheel 8 I form a number of radial slots or recesses 8² into one or other of which the inner end 19' of the stud 19 is adapted to enter, the engagement of the said stud with one of the said recesses locking or clutching the spur wheel 8 to the shaft 7 on which it is mounted, so that the motion transmitted to the wheel 8 from the tappet shaft through the gears 9, 10 and 11 is imparted to the shaft 7 to cause the sand roll 1 to be revolved to effect the positive take-up of the fabric as it is woven. The parts normally remain in these positions, which are those shown in the drawing, so long as weaving is proceeding, but in the event of the weft fork detecting absence or breakage of weft, the movement of the weft fork slide in the ordinary manner to rock 100 105 110

the stop or change rod 12, rocks the lever 13 and causes the arm or extension 13³ of the arm 13 to be moved inwardly or toward the lever 15. This movement of the arm 13³ through the pin or lug 14 thereon, causes the upper end of the lever 15 to be forced inwardly or in the direction of the arrow C, Fig. 2, and the lower end 15' of said lever to be moved outwardly or in the opposite direction as indicated by the arrow D, Fig. 1.

10 The engagement of the circular portion or ring 15³ of the lever 15 with the collar or flange 20 causes the stud 19 to be forced outwardly, against the action of the spring 21, and its inner end 19' to be moved clear of the opening or recess 8² in which it happened to be engaged.

15 The wheel 8 is thereupon permitted to rotate idly upon the shaft 7 which thus ceases to be driven, so that the motion of the sand roll 1 is immediately arrested and the take-up ceases.

20 On normal conditions being re-established and the weft fork slide moving back to normal position, the circular portion or ring 15³ is released and the stud 19 is forced back against the face of the boss 8'. The wheel 8 being constantly driven, the inner end of the stud 19 is forced into the first opening or recess 8² which is presented opposite thereto, and the wheel 8 is again locked to the worm shaft 7 to cause motion to be transmitted to the sand roll to take up the fabric.

25 35 The spring-actuated stud 19 is provided on its outer end with a knob or device 19² to enable it to be drawn outwardly by hand to free it from the boss 8' of the wheel 8, and when thus drawn out it serves as a handle to the arm 18 and enables the operative to rotate the worm shaft 7 forwardly or backwardly at will to wind up or let back the fabric.

40 45 The pin 14 may be carried by an extension on the boss of the usual fixed arm 22 instead of being carried by an extension on a separate arm loosely mounted on the stop or change rod as shown.

50 55 The construction and arrangement of the parts may be varied without departing from my invention. If the improvements are applied in conjunction with a weft feeler motion, the lever 15 may be arranged to be rocked by a part carried by the change rod, or by a part actuating said rod, or by some other part of the motion which will bring my improvements into operation immediately the weft feeler detects exhaustion of weft.

60 65 Having thus described my invention, what I claim as new and desire to secure by Letters Patent is:—

1. In a take-up motion for looms, the combination of a shaft, a sand or take-up roll, 70 means for driving the latter from the for-

mer including a continuously driven pinion or spur wheel having a series of openings or recesses, an arm fixed to said shaft and carrying a pin adapted to engage in one or other of said openings or recesses, said pin being provided with a flange or collar, a lever having a portion underlying said flange or collar, and means to rock said lever to disengage the pin from said openings or recess when filling is absent or substantially 75 exhausted.

2. In a loom take-up motion, the combination with a shaft carrying a worm by which motion is transmitted to the sand roll and a driven spur wheel loosely mounted on said shaft, of an arm fast on said shaft, a spring actuated stud carried by said arm, a boss on said spur wheel having in its face a series of radial openings or recesses in one or other of which the inner end of the spring 80 actuated stud is adapted to engage, a pivoted lever having a circular portion or ring encircling or concentric with the said boss, a flange, collar or the like on the stud adapted to be engaged by said ring or circular portion, and means to cause said lever to be rocked, on indication by the weft fork motion of breakage or absence of weft, or on indication by the weft feeler motion of weft exhaustion.

3. In a take-up motion for looms, the combination of a pinion or spur wheel continuously operated by a going part of the loom, a take-up, means for transmitting motion from said pinion or spur wheel to the take-up including a shaft, an arm carried by said shaft and having a pin for operatively engaging the pinion or spur wheel and said shaft, a flange or collar mounted on said pin, a lever having a part underlying said flange or collar and bearing upon a face of the pinion spur wheel, and means for causing said lever to move the pin and interrupt the operative relation between the shaft and pinion or spur upon detection of 100 filling absence or substantial exhaustion.

4. In a take-up motion for looms, the combination of a shaft, a take-up or sand roll, means for driving the latter from the former, said means including a continuously driven pinion or spur wheel, a combined manually and automatically controlled pin device for operatively connecting and disconnecting the shaft and pinion or spur wheel and having a hand engaging head and a flange or collar, a lever having a bearing portion on which said flange or collar travels, and means for actuating the lever to automatically disengage the operative connections between the pin and pinion or spur wheel upon detection of filling absence or substantial exhaustion.

5. In a take-up motion for looms, the combination of a shaft, a worm fixed thereto, a take-up or sand roll, operating con-

nections between the worm and take-up or sand roll, a continuously driven pinion or spur wheel mounted on said shaft and having a series of openings or recesses, an arm 5 mounted on the shaft and carrying a spring actuated pin for engaging any one of the said series of openings or recesses, a flange or collar on the pin, a lever having a bearing portion upon which said flange or collar 10 rests, and means for tilting the lever to dis-

engage the pin from the openings or recesses upon absence or substantial exhaustion of filling.

In testimony whereof I affix my signature in the presence of two witnesses.

DENIS M. HOLLINS.
